UNITED STATES PATENT OFFICE

WINIFRED L. GIBBONS, OF PROVIDENCE, RHODE ISLAND, ASSIGNOR TO C. G. KING & CO., INC., OF PROVIDENCE, RHODE ISLAND

DESIGN FOR A SHOE ORNAMENT OR SIMILAR ARTICLE

Application filed March 18, 1932. Serial No. 43,225. Term of patent 7 years.

To all whom it may concern:

Be it known that I, WINIFRED L. GIBBONS, a citizen of the United States, residing at Providence, in the county of Providence and State of Rhode Island, have invented a new, original, and ornamental Design for a Shoe Ornament or Similar Article, of which the following is a specification, reference being had to the accompanying drawings, forming part thereof.

In said drawings, Fig. 1 is a front face view, and Fig. 2 is an edge view of a shoe ornament showing my new design.

I claim:

The ornamental design for a shoe ornament or similar article as shown.

Signed at Providence, in the county of Providence and State of Rhode Island, this 17th day of March, A. D. 1932.

WINIFRED L. GIBBONS.
